(57) **CLAIM**

The ornamental design for an EGR trap, as shown and described.

DESCRIPTION

FIG. 1 is a perspective view of an ornamental design for an EGR trap according to the invention.

FIG. 2 is a front view of the EGR trap of FIG. 1.

FIG. 3 is a rear view of the EGR trap of FIG. 1.

FIG. 4 is a left view of the EGR trap of FIG. 1.

FIG. 5 is a right view of the EGR trap of FIG. 1.

FIG. 6 is a top view of the EGR trap of FIG. 1; and,

FIG. 7 is a bottom view of the EGR trap of FIG. 1.

The broken line shown in the drawings are for the purpose of illustrating portions of the article that form no part of the claimed design.
